UNITED STATES PATENT OFFICE.

JAMES B. ERWIN AND ORLANDO R. ERWIN, OF MILWAUKEE, WISCONSIN, ASSIGNEES
TO FOAMITE FIREFOAM COMPANY, OF NEW YORK, N. Y., A CORPORATION OF
DELAWARE.

APPARATUS FOR EXTINGUISHING FIRES.

1,403,596.

Specification of Letters Patent. Patented Jan. 17, 1922.

Application filed February 9, 1917. Serial No. 147,529.

To all whom it may concern:

Be it known that we, JAMES B. ERWIN and ORLANDO R. ERWIN, citizens of the United States, residing at the city of Milwaukee, county of Milwaukee, and State of Wisconsin, have invented new and useful Improvements in Apparatus for Extinguishing Fires, of which the following is a specification.

10 This invention relates to an apparatus for automatically generating and distributing a fire extinguishing foam for extinguishing fires in buildings, boats, etc., and it pertains more especially to that class known as automatic sprinkler systems.

15 It is a well known fact that on certain classes of fires, such as occur with highly inflammable liquids, water has little or no extinguishing effect, often tending to increase the fire by spreading it, whereas if a sufficient quantity of a suitable foam is properly applied to such fires they may be readily extinguished.

20 The principal object of this invention is to provide an especially effective combination of well known efficient apparatus adapted to employ suitable foam producing solutions which when mixed will form a fire extinguishing foam. Our apparatus may be 25 readily installed in such buildings as garages, paint and varnish works, petroleum refineries and the like, in which highly inflammable liquids, oils, greases, etc., are either stored or handled.

30 Further objects of the invention will appear more fully hereafter.

Referring to the drawings:

Figure 1, is a side elevation, part in vertical section, of one form of arrangement of 40 a portion of the invention, shown in operative connection with two solution reservoirs located on the roof of a building.

Figure 2, is a similar view to that shown in Figure 1, showing a modified form of the 45 invention in connection with a compressed air tank.

Figure 3, is a vertical sectional view of a preferred form of solution controlling valve.

Like parts are identified by like reference 50 characters throughout the several views.

Before describing the drawings in detail, we will give a brief description of the general operation of the invention, and the foam producing solutions employed. Sprinkler heads 1, of ordinary construction, but

preferably of a larger size than those now on the market, are located in the usual manner near the ceilings 2 and other exposed parts of a building or other structure, and are operatively connected directly to foam generating chambers 3 as shown in Figure 2, or indirectly to the foam generating chamber 5 by means of suitable piping 10, as is shown in Figure 1. Two separate reservoirs 6 and 7 are provided to contain the two special liquids A and B which when mixed will form the fire extinguishing foam, and these liquids may be briefly described as follows: The solution A is preferably composed of water, sodium bicarbonate, and a foam producing substance, for example saponin which is an extract of soap bark. The solution B may be in the nature of any suitable acid solution, and when the two solutions are mixed a foam lasting a long time 75 is produced. When a fire occurs in the vicinity of one of the sprinkler heads 1, the strut 8 thereof fuses in the usual way, which releases the air pressure or other medium holding back the two separating solutions. 80 The two solutions, thus released, are brought together, through piping, to a mixing chamber and therein thoroughly mixed to form the foam which, under the added pressure of the gas generated, escapes under increased 85 pressure at the fused sprinkler head, and the said foam is thereby automatically spread in all directions upon the fire in the vicinity of such head.

Referring now more especially to Figure 90 1, the system therein shown is intended to represent what is commonly termed the "wet system" of installation, that is, the distributing pipes 10, fittings 11, etc., are filled with liquid which, in this case, is preferably the 95 alkaline solution A contained in the reservoir 6. The other liquid B in the reservoir 7, being an acid solution should preferably be normally kept out of the mixing chambers and distributing system of piping owing 100 to its corrosive effect thereon, and its containing reservoir 7 is therefore preferably provided with an acid proof lining 13, or the equivalent. To normally prevent the said acid solution B from entering the risers 12 105 and piping 10, we employ what is commonly termed a dry pipe valve 14, which is herein shown and described in detail with reference to Figure 3. Reference still being had to Figure 1, the reservoir 6 is shown located 110

at a greater elevation above the roof 20' of the building than that of the reservoir 7, whereby a greater pressure is normally maintained in distributing pipes, etc., which will 5 counteract the pressure of the acid solution B in the reservoir 7 and keep such solution out of said system until required.

This is accomplished by means of the so-called dry-pipe valve 14 shown in vertical 10 section in Figure 3. This comprises the two-seated valve 15, valve seats 16 and 17 therefore, all operatively installed in the two-piece housing as shown, the upper section 18 of which is provided with a flanged inlet 19, for 15 connection by bolts, not shown, to the solution reservoir 7, and the lower section 20 is similarly provided with a flanged outlet 21 for connection by means of bolts, not shown, to the distributing system of pipes or risers. 20 The two sections 18 and 20 are connected together to form a tight joint at 22 by means of the annular flanged connections 23, 23', through bolts, or any suitable means.

In operation, air or other fluid under pressure 25 enters through port 21 and exerts pressure on the lower side 25 of the valve 15, thus holding the same against both its seats 16 and 17, and thereby tightly closing the port 19. When any of the sprinkler heads 1 30 of the system open up, the air or other fluid pressure in the distributing pipes falls and valve 15 drops upon the stops 30, which permits the liquid on the upper side of the valve 15 to descend, through the open by-paths 31 35 surrounding said valve 15, to the foam generating chamber and distributing system.

To prevent back pressure of the foam generated in the chamber 5, of Figure 1, from closing the said valve 15 in the housing 14, 40 we have provided a pressure equalizing by-pass duct 35, which provides open communication between the said foam generating chamber 5 and the upper ends of both said solution reservoirs through the branch duct 45 37 and 38.

Referring to Figure 2, the system therein shown represents the application of what is commonly known as the "dry-pipe system" of installation, namely all piping, fittings, 50 foam generating chambers, etc., connecting the sprinkler heads 1 with the over head gravity reservoirs 6 and 7, are filled with air under sufficient pressure to normally hold the dry-pipe valves 14 in their closed positions, thereby normally retaining the solutions A and B in their respective reservoirs. Should any one or more of the sprinkler heads 1 open, the air pressure in the distributing system falls, resulting in the simultaneous 55 discharge of the two separated solutions into the foam generating chambers 3, in operative connection with the sprinkler heads as above described.

The tank 40 represents a compressed air 60 storage tank in operative connection with a

source of supply, not shown, through the duct 41 and check valve 42, and open communication is had with the distributing piping through the duct 43, while 44 is a pressure gauge of ordinary construction in connection with said compressed air tank 40. 70

Many modifications in any of the above described systems may be made without departing from the general scheme of this invention. 75

What we claim is:

1. In an automatic fire extinguishing apparatus, a plurality of solution reservoirs holding component solutions which, when comixed, produce a fire extinguishing foam, 80 solution discharge means comprising a discharge pipe for each reservoir and connected for solution communication with such reservoirs, a distributing piping system connected to the solution discharge means and including provisions for comixing the solutions to generate a foam, automatic valve mechanism in said solution discharge means and located between the distributing piping system and the reservoirs; the said automatic 85 valve mechanism being normally closed under fluid pressure in the distributing piping system and fusible means in the free end of the said distributing piping system, the automatic valve mechanism being adapted 90 to be opened upon the fusing of the fusible means to permit the solutions to flow from the reservoirs for comixture to provide a 95 fire extinguishing foam.

2. In an automatic fire extinguishing apparatus, the combination with a plurality of reservoirs, adapted to contain different liquids, which, when mixed form a fire extinguishing foam, of a pipe connected to each reservoir at the bottom thereof to permit the liquid from the reservoirs to be forced therethrough under pressure by gravity, an automatic valve interposed between each pipe and its respective reservoir, mixing chambers and fusible extinguishing 100 heads connected to the free ends of the pipes, the automatic valves being normally closed by air or fluid under pressure in said pipes to prevent the mixing of the different fluids in said reservoirs, said valves being actuated upon the fusing of a fusible extinguishing head whereby the liquids may mix 105 and form a fire extinguishing foam for the purpose specified. 110

3. In an automatic fire extinguishing apparatus, a plurality of solution reservoirs holding component solutions which, when comixed, produce a fire extinguishing foam, solution discharge means comprising a discharge pipe for each reservoir and connected 115 for solution communication with such reservoir, a distributing piping system including a foam mixing chamber connected to said solution discharge means, automatic valve mechanism in said solution discharge means 120 125 130

and located between the distributing piping system and the reservoirs; the said automatic valve mechanism being normally closed under fluid pressure in the distributing piping system and fusible extinguishing means connected to a free end of the said distributing piping system; the automatic valve mechanism being adapted to be opened upon the fusing of the fusible extinguishing means to permit the solutions to flow from the reservoirs to the mixing cham-

ber for the production of the foam and the issuing of the foam from the said free end of the piping system.

In testimony whereof we affix our signatures in the presences of two witnesses. 15
